UNITED STATES PATENT OFFICE.

LYLE N. GILLIS, OF ROSE CREST, VIRGINIA, ASSIGNOR, BY DIRECT AND MESNE ASSIGNMENTS, OF ONE-HALF TO THE FLOOROLA CORPORATION, OF BALTIMORE, MARYLAND, A CORPORATION OF DELAWARE, AND ONE-HALF TO ERNEST J. NEWCOMER, OF BALTIMORE, MARYLAND.

WAX DISTRIBUTOR FOR FLOOR POLISHERS.

Application filed February 12, 1924. Serial No. 692,298.

This invention relates to floor polishing machines of the general type described and shown in my copending patent filed September 7, 1923, and bearing the Serial Number 5 661,424.

More particularly the invention relates to a floor waxing device for use in connection with such machines.

One important object of the invention is 10 to provide an improved device of this kind wherein the wax is distributed and spread evenly on the floor by a novel arrangement of the parts.

A second object of the invention is to provide 15 a novel combination of wax emitting device and polishing brush.

A third object of the invention is to provide an improved distributing can or container for such use.

20 With the above and other objects in view as will be hereinafter apparent, the invention consists in general of certain novel details of construction and combinations of parts hereinafter fully described, illustrated 25 in the accompanying drawings and specifically claimed.

In the accompanying drawings like characters of reference indicate like parts in the several views, and:

30 Figure 1 is a plan view of one form of the device.

Figure 2 is a vertical longitudinal section through the center of the device.

Figure 3 is an end view of the device.

35 Figure 4 is a plan view of a modified form.

Figure 5 is a vertical longitudinal section of the device as shown in Figure 4.

Figure 6 is an end view of the modified 40 form.

Figure 7 is a detail elevation of the improved can or container, the view showing the slipping cover in section.

In each of the forms here shown there is 45 provided a back member 10 having securing notches 11 at its ends and being provided with a centrally disposed opening 12. In the form shown in Figure 1 this opening is cylindrical throughout, the brush in this form being oblong. In the other form the opening 12 has a frusto-conical lower portion 13. Bristles 14 extend downwardly from the back around the opening and are

preferably arranged in staggered tufts so as to leave a central space completely walled in by bristles. However, where an oblong brush is used it may sometimes happen that only a single row of tufts can be employed.

55 In the form shown in Figure 1 the can 15 is of ordinary cylindrical shape having a 60 top 16 and fits into the opening 12, being there held by suitable means such as the bayonet lock 17.

65 In the form shown in Figure 5 the can has a central frusto-conical portion 18 having a cylindrical lower portion 19 closed at its bottom. This frusto-conical portion is provided with a collar 20 at its upper end and at the lower end of the collar there is a top closure 21. Suitable means such as 70 the bayonet lock 22 hold the neck in the opening 12. In each case escape openings 23 are provided in the side wall of the can adjacent its bottom.

75 A cap 24 may be used to close the escape openings for packing or storing.

80 In use rapid revolution of the can ejects the contents through the openings 23 and the wax thus ejected runs down the bristles and is rubbed on the floor.

Having thus described the invention, what is claimed as new, is:

85 1. The combination with a brush back having bristles carried thereby, and having an opening therein, of a wax distributing can mounted in said opening and having peripheral escape openings arranged therein in directions transverse to the direction of the bristles for discharging the contents of the can laterally onto the bristles. 90

95 2. The combination with a brush back having bristles extending outwardly therefrom, and having an opening therein, of a wax distributing can mounted in said opening and having peripheral escape openings arranged therein in directions transverse to the direction of the bristles for discharging the wax laterally onto the bristles to be applied thereby to the surface being treated. 100

105 3. The combination with a brush head having polish applying media extending outwardly therefrom, and having an opening therein, of a wax distributing can mounted in said opening and having a portion thereof protruding therefrom, said protruding portion of the can having an escape

opening arranged therein, in a direction transverse to the normal positional direction of the polish applying media.

4. The combination with a brush back having bristles carried thereby, and having an opening therein, of a wax distributing can mounted in said opening and protruding therefrom, said protruding portion having a peripheral escape opening arranged 10 therein in a direction transverse to the normal direction of the bristles.

5. The combination with a rotary brush head having an opening therein, and polish applying media extending outwardly from the head in a direction approximately parallel to the axis of rotation of the brush head, 15 of a wax distributing can mounted in said opening and having a discharge orifice in position to discharge the contents upon the surrounding wall of polish applying media 20 upon the rotation of the brush head and can.

6. The combination with a polishing brush having polish applying media carried thereby, of a wax distributing can carried by said brush, said can having an escape 25 opening arranged therein in a direction transverse to the normal positional direction of the polish applying media, for discharging the contents thereof onto the polish applying media.

7. The combination with a brush head having an opening therein, and polish applying media extending outwardly from the surface of the head and arranged about the open end of the opening forming a wall, of 30 a wax distributing can mounted in said opening and having discharge orifices approximately in the outer edge thereof for discharging the contents onto the surrounding wall of polish applying media.

In testimony whereof I affix my signature.
L. N. GILLIS.
